UNITED STATES PATENT OFFICE.

PERCIVAL HAMMER TROUTMAN, OF CANON CITY, COLORADO.

ORCHARD-HEATER.

976,013.

Specification of Letters Patent. Patented Nov. 15, 1910.

Application filed July 10, 1909. Serial No. 507,010.

To all whom it may concern:

Be it known that I, PERCIVAL HAMMER TROUTMAN, a citizen of the United States, residing at Canon City, county of Fremont, 5 and State of Colorado, have invented certain new and useful Improvements in Orchard-Heaters; and I do declare the following to be a full, clear, and exact description of the invention, such as will enable others skilled 10 in the art to which it appertains to make and use the same, reference being had to the accompanying drawings, and to the letters and figures of reference marked thereon, which form a part of this specification.

15 My invention relates to improvements in orchard heating devices, my object being to provide an attachment for the liquid fuel receptacle of an orchard heating device, whereby the burning of the fuel may be 20 regulated and controlled.

Where my improved device is employed, the receptacle may be made of the maximum capacity. Where it is required to burn fuel rapidly, the attachment will not be used, but 25 where the burning capacity of a relatively large receptacle is greater than desired in any particular instance, my improved attachment is applied, whereby the rapidity with which the fuel burns is lessened, owing 30 to the reduced fuel surface exposed to the fire.

My improved attachment consists of a top rim engaging the upper edge of the receptacle, extending horizontally inward, where- 35 by the top opening is reduced in size, the said rim having a depending member, ex- tending downwardly into the liquid fuel, when the receptacle is full or approximately filled with fuel. This depending member 40 may be of any desired length. However after the fuel is burned below the depending member the available burning surface of the liquid is virtually diminished to har- monize with the circle described by the said 45 member, since the outer portion of the fuel receptacle is closed at the top, thus prevent- ing direct upward draft. In other words the diminished draft diminishes the burning 50 capacity of the device, thus limiting the amount of fuel consumed within a given time.

Having briefly outlined my improved construction, I will proceed to describe the same in detail, reference being made to the 55 above drawing, in which is illustrated an embodiment thereof.

In this drawing: Figure 1 is a perspective view of an orchard heating device, equipped with my improved attachment, the latter being partly broken away at the top. 60 Fig. 2. is a central vertical section of the same. Fig. 3. is a perspective view of the attachment shown in detail.

The same reference characters indicate the same parts in all the views. 65

Let the numeral 5 designate the body of a receptacle adapted to hold liquid fuel. As shown in the drawing, this receptacle is largest at the top and slopes gradually toward the lower extremity, where it is smallest. The bottom 6, of the receptacle, has a central opening 7, surrounded by a centrally located upwardly projecting tube or chimney 8, which is largest at the bottom and diminishes gradually toward its upper 75 extremity.

Near the top of the chimney openings 9, are preferably formed. The body 5 of the receptacle, is mounted on a depending cylindrical support 10, having a draft opening 80 12. While this form of orchard heater is well adapted to utilize my improvement, it is evident that the latter may be advantageously employed with any ordinary receptacle adapted to hold liquid fuel, when 85 it is desired to diminish its burning capacity.

It often becomes necessary to vary the heating capacity of these devices. For instance in fruit sections, the owners have 90 heating devices distributed through the orchards and other localities to be protected from the frost, the number of devices em- ployed being those required in the case of a sudden and relatively low fall in the tem- 95 perature. In other words, the ordinary equipment must be sufficient to protect these localities in the event of a maximum fall in temperature, within a comparatively short time. 100

Now in the event that the fall is not so great, but still sufficient to require some protection, my improved attachment will be available, and it is only necessary to simply set it on the device, the rim of the attachment resting upon the upper edge of the receptacle, while the depending member ex- tends downward thereinto, preferably enter- 105 ing the liquid fuel when the receptacle is full or approximately full. 110

Specifically my improved attachment as illustrated in the drawing, consists of a hori-

horizontal circular part 13, whose outer edge is bent downwardly as shown at 14, forming a flange for retaining the attachment in place upon the receptacle. The lower extremity of this retaining flange is normally of slightly less circumference than the outer circumference of the bead 15, surrounding the upper edge of the receptacle 5, whereby it is necessary to exert some pressure upon the attachment in order that its retaining flange may be sprung outwardly slightly, while passing the greatest circumference of the bead, after which the lower edge of the flange springs into place below the bead holding the attachment securely in place thereon.

At the inner edge of the part 13, is located the depending member 16, which may be of any desired length, preferably extending below the surface of the liquid when the receptacle is full, thereby reducing the surface area of the liquid exposed to the air, and consequently reducing the burning capacity of the device.

From the foregoing description the use of my improved device will be readily understood, and need not be further described in detail.

Having thus described my invention, what I claim is:

1. The combination with a liquid fuel receptacle, of an open ended chimney for feeding air to the surface of the liquid fuel, an attachment for reducing the surface area of the liquid exposed to the atmosphere, and consisting of a removable device engaging the outer edge of the receptacle, extending

inwardly partially closing the top of the receptacle, and having a depending annular member, extending into the receptacle a suitable distance for the purpose set forth. 40

2. The combination with an orchard heater including a receptacle for liquid fuel, of an open ended chimney for feeding air to the surface of the liquid fuel extending centrally through the receptacle, a removable attachment adapted to rest upon the outer edge of the receptacle, partially closing the top of the receptacle, and having an annular depending member of suitable length 45 50 extending into the receptacle, for reducing the surface area of the liquid exposed to the atmosphere, substantially as described.

3. The combination with an orchard heater including a liquid fuel receptacle, an open ended chimney for feeding air to the surface of the liquid fuel, a circumferential bead at the top of the receptacle, and a removable attachment having a flange adapted to yield sufficiently to slip over the bead for 55 60 retaining purposes, the said attachment being supported upon the upper edge of the receptacle extending into the latter partially closing the top thereof, and having a depending annular member extending downwardly into the receptacle for reducing the surface area of the liquid exposed to the atmosphere, substantially as described. 65

In testimony whereof I affix my signature in presence of two witnesses.

PERCIVAL HAMMER TROUTMAN.
